SWING

Robert M. Rink, Goshen, Ind., assignor to The Goshen Manufacturing Company, Inc., Goshen, Ind.

Application November 20, 1950, Serial No. 196,562

2 Claims. (Cl. 155—63)

1

This invention relates to improvements in swings.

The main objects of this invention are:

First, to provide a swing which is well adapted for home or playground use and which is easily operated and at the same time has a maximum of safety.

Second, to provide a swing having these advantages which provides exercise for the users.

Third, to provide a structure having these advantages which may be transported or moved about and at the same time has a support which is strong and rigid.

Objects relating to details and economies of the invention will appear from the description to follow. The invention is defined and pointed out in the claims.

A preferred embodiment of the invention is illustrated in the accompanying drawing, in which:

Fig. 1 is a perspective view of a swing embodying my invention shown in normal position by full lines and in an actuated position by dotted lines.

Fig. 2 is an enlarged fragmentary view in section on a line corresponding to line 2—2 of Fig. 1.

Fig. 3 is an enlarged fragmentary view on a line corresponding to line 3—3 of Fig. 1.

The embodiment of my invention illustrated comprises pairs of downwardly diverging uprights 1—1 connected at their lower ends by means of the base bar 2. The upper ends of the uprights of the pair are connected by a coupling 3, which is fixedly secured thereto. The pairs of uprights are connected by the cross bar 4 fixedly secured to the couplings 3. The connections are conventionally indicated at 5.

Cross arms 6 are disposed on the under side of the cross bar 4 and fixedly secured thereto as by welding indicated at 7. The bowed combined hangers and brace members 8 are disposed over the cross bar and welded thereto at 9, the arms of these members 8 being fixedly secured to the cross arms adjacent their ends as indicated at 10. Pairs of hanger rods 11 are pivotally connected at their upper ends to the ends of the cross arms by means of the pivots 12.

A platform or footrest 13 consisting of the side bars 14 and the slats 15 is pivotally mounted at 16 on the lower ends of the hanger rods 11. The pivots 12 connecting the upper ends of the hanger rods to the cross arms and the pivot 16 connecting the lower ends of the rods to the platform or footboard are spaced so that corresponding rods of the pairs are in parallel relation permitting the rods to swing on their pivots 12. Seat bars 17 are pivotally mounted at 18 on the hanger rods in

2

vertically spaced parallel relation to the platform. These seat bars are desirably disposed on the inner sides of the hanger rods, and they are provided with seats 19 at their outer ends.

5 The hand bars 20 connect the pairs of hanger rods and are positioned to be grasped by a child for so-called pumping manipulation of the swing when a child is standing. The hanger rods 11 are so spaced relative to each other that a child's head or even shoulders may pass between the same in the event that the swing is manipulated or operated on a high stroke so that there is little likelihood of a child being injured. The hanger rods may be grasped in any position above the seat that may be convenient for the particular user. While the swing is designed for two children, it may be successfully used by a single child.

Another advantage of the structure is that there is a full seat for the child as distinguished from the so-called saddle type of seat. This allows the full use of the feet and legs in manipulating the swing so that the arms, legs and shoulders, and in fact the body generally is exercised in the manipulation of the swing. The bars 20 may also be used as a trapeze if desired, or a child may stand on the seat and grasp the bars 20 for manipulation of the swing, thereby providing a variety of manipulations. In Fig. 3, the details of the pivots 18 are illustrated, these being in the form of bolts passed through the seat bars 17 and provided with bushings 21 within openings 22 provided therefor in the hanger rods 11. The pivots 12 and 16 are desirably of the same type as shown in Fig. 3.

35 Braces 23 connect the uprights 1 with the cross bar 4. This provides a very rigid structure even when made of comparatively light material. The uprights, cross bar and hanger rods are desirably of tubular stock.

I have illustrated and described my invention in a highly practical embodiment thereof. I have not attempted to illustrate or describe other embodiments or adaptations, as it is believed that this disclosure will enable those skilled in the art to embody or adapt my invention as may be desired.

Having thus described my invention, what I claim as new and desire to secure by Letters Patent is:

50 1. In a swing, the combination of a support comprising a crossbar, crossarms disposed in spaced relation on the underside of said crossbar and fixedly secured thereto, bowed hanger and brace rods disposed over said crossbar and fixedly secured thereto and to the crossarms adjacent

their ends, pairs of hanger rods pivotally mounted on the crossarms, a platform pivotally mounted on the lower ends of said hanger rods with the corresponding hanger rods of the pairs in spaced parallel relation, seat bars disposed between the pairs of hanger rods and pivotally connected thereto in vertically spaced parallel relation to the platform, seats mounted on the outer ends of the platform, seats mounted on the outer ends of said seat bars, and hand bars extending between the pairs of hanger rods in vertically spaced relation to said seat bars. 10

2. In a swing, the combination of a support comprising a crossbar, crossarms disposed in spaced relation on the underside of said crossbar and fixedly secured thereto, bowed hanger and 15 brace rods disposed over said crossbar and fixedly secured thereto and to the crossarms adjacent their ends, pairs of hanger rods pivotally mount-

ed on the cross arms, a platform pivotally mounted on the lower ends of said hanger rods with the corresponding hanger rods in spaced parallel relation, seat bars disposed between the pairs of hanger rods and pivotally connected thereto in vertically spaced parallel relation to the platform, and seats mounted on the outer ends of said seat bars. 5

ROBERT M. RINK.
